UNITED STATES PATENT OFFICE

EDWARD J. GULICK, OF ELKHART, INDIANA

ENGINE LUBRICATING DEVICE

Application filed December 6, 1929. Serial No. 412,250.

My invention relates to internal combustion engines, and particularly to the means for engine lubrication.

The present prevailing practice in internal combustion engine lubrication, especially motor car engines, consists in pumping oil from a pool carried in the engine base and circulating it through the lubrication circulatory system to the various engine bearings. 5
10 In such a system dirt, water, carbon, gasoline, and other deleterious substances accumulate in the engine base, mix with the lubricant, and are continuously circulated with the lubricant to the engine bearings, thereby impairing the quality of the lubricant.

And in such a system considerable water accumulates in the engine base in winter by condensation, and otherwise, and when a motor car stands idle, the water forms a pool 20 in the bottom of the engine oil-pan and freezes in severe winter weather, whereby the oil suction pipe, which extends to the oil-pan bottom, is closed and the lubrication system is rendered useless.

The principal object of this invention is to improve and simplify the mechanism shown and described in my Letters Patent of the United States, No. 1,369,239, of Feb. 22, 1921.

Another object of the invention is to effect a direct communication between the oil pump and the oil suction pipe.

A third object of the invention is to effect a rigid connection between the oil suction pipe and the float therefor.

Still another object is to provide improved means for attaching the screen to the suction-pipe float.

A further object is to provide means for spacing the inlet orifice of the suction pipe from the oil-pan bottom where water and other deleterious matter may have accumulated.

A still further object is to provide baffle means for causing the lubricating oil to flow thereover before entering the suction pipe.

Other and more specific objects of the invention are mentioned and described herein.

50 The preferred embodiment of the inven-

tion is illustrated in the accompanying drawings, wherein

Figure 1 is a section in elevation through an engine base to which my invention is applied;

Fig. 2 is an enlarged view in elevation, partially broken away, showing the suction pipe, the float, and the flanged connection to the pump;

Fig. 3 is a section taken on line 3—3 of Fig. 2;

Fig. 4 is a bottom plan view of the float and screen, broken away;

Fig. 5 is a section taken on line 5—5 of Fig. 2;

Fig. 6 is a view similar to Fig. 2 illustrating a modification of the device in combination with baffle means and stop means for limiting the movement of the float and suction pipe;

Fig. 7 is a plan view of the baffle plate and a portion of the pump elbow;

Fig. 8 illustrates a plan view of a modified form of the baffle plate;

Fig. 9 illustrates still another modification of the baffle plate; and

Fig. 10 shows a side elevational view of the baffle plate illustrated in Fig. 8.

Similar numerals of reference indicate like parts throughout the several views on the drawings.

Referring to the details of the drawings the numeral 1 represents the crank-case of a multi-cylinder internal combustion engine within which is mounted the usual crank-shaft 2 having the usual bearings 3, 3 and an oil-pan 4 suitably connected with said crank-case. The numeral 5 indicates an oil circulation pump suitably mounted in the engine base and which may be operated by the upright shaft 6, the latter being driven by the gears 7 and 8 carried, respectively, by said shaft and the engine cam shaft 9.

The oil-pan 4 contains the usual pool of lubricant 10 adapted to be circulated to the shaft bearings 3, 3 through the pump delivery pipes 12, 12. The oil pump 5 may be of any suitable type, but as illustrated, it is a gear pump of a well known design, being provided with the suction inlet 13 which

is in communication with the bore 14 of the depending suction elbow 15 which may be fastened to said pump by screws 16. The outer end of the elbow 14 has its axis disposed in a horizontal plane and may be counter-bored at 17 to receive the cylindrical tubular end 18 of the suction pipe elbow 19 with which the suction pipe 20 is rigidly connected, there being sufficient clearance between section 18 of said elbow and said counter-bore to effect a hinge action therebetween.

The elbow 19 may be provided with the annular peripheral flange 21 which may engage the end wall of the counter-bore 17 and which is held in juxtaposition by a furcated retaining plate 22 secured to the end face of the elbow 15 by screws 23, an arcuate portion of which plate overlies a part of said flange 21.

The outer end of the suction pipe 20 carries the float element 24 rigidly connected therewith, the latter being adapted to float upon the surface of the oil pool 10 to buoyantly sustain the pipe 20 therein to cause the latter to swing in a vertical plane as the level of said oil pool may vary. Float element 24 may be annular in formation and is preferably made of thin sheet metal, and may comprise the bottom and side wall section 25 and 26, respectively, struck from a single sheet of ductile metal, and the annular cover 27 secured to the upper edge of said side-wall section by solder, or otherwise in any suitable manner. The suction pipe 20 extends through a suitable aperture in the float side-wall 26 to the center of the float body and has its downwardly turned inlet elbow 28 rigidly secured, by solder or otherwise, in the aperture 29 formed centrally in the float bottom wall 25, whereby the orifice of the elbow 28 is held in permanent communication with the pool of lubricant adjacent its surface regardless of the varying level of the oil pool.

The numeral 30 indicates a wire gauze screen applied to and covering the bottom of the float to exclude impurities and deleterious matter from the oil circulatory system, said screen being spaced from the float bottom 25 by a series of depending radially formed ribs 31 stamped in said bottom to provide oil conduit channels between said ribs, whereby the oil may move freely to the inlet orifice of the pipe elbow 28. The screen 30 may be secured to said float bottom in any suitable manner, but the preferred method is illustrated in Fig. 2 of the drawings and comprises the annular inwardly extending groove 32 stamped in the bottom edge of the float side-wall section 26, and extending circumferentially thereof, within which groove the upwardly and inwardly hooked outer periphery 33 of the screen is clamped by compressing the walls of said groove upon said screen.

The retaining plate 22 may be provided with the integral furcations 34 and 35, which

are curved outwardly and arranged in spaced relation, respectively, above and below the elbow 19 and adapted to serve as stop elements to limit the upward and downward movement of the pipe 20.

In the modification illustrated in Fig. 6 the construction of the float 24 contemplates an upwardly dished lower wall section 36 suitably apertured at 29 to receive the elbow 28 of the pipe 20. To accommodate such a structure the pipe 20 may be upwardly curved or bent at 37 within the float. And in Fig. 6 the numeral 38 represents a stationary annular oil control or baffle element, or plate, which, as illustrated, is integral with the lower prong of the retaining plate 22, and which may have a depending leg 39 at its forward end to hold or support said baffle plate in spaced relation with the bottom of pan 4, whereby the oil is caused to flow over the outer periphery of said baffle, from all points thereof, to the float center, in a substantially horizontal plane, before it enters the inlet orifice of the pipe 20. In this manner any deleterious substance on the oil pan bottom is not readily taken into the suction pipe or picked up by the screen 30.

To control the movements of the float 24 upper and lower stop means are provided, and in Fig. 6 the upright post 39, secured to the plate 38 at 40, has laterally bent upper and lower stop elements 41 and 42, respectively, preferably integral therewith, the latter serving also to space the float screen 30 from the upper face of the baffle 38 when the float is at its lowest position. Under some circumstances it may be advisable to limit the upward travel of the float to a plane below the stop 41, and even confine it rigidly in contact with the lower stop 42. There is therefore provided a headed upright adjusting stop screw 43 threaded into the enlarged end 44 of the prong 34 of plate 22 (Fig. 6) and adapted to contact with the elbow 19 and which may be manually adjusted to confine the float in contact with stop 42.

Obviously, the stop screw 43 may be so adjusted as to permit limited upward movement from the stop 42, if so desired.

In Figures 8 and 10 a modified form of the baffle plate 38 is shown, wherein the body thereof is segregated from plate 22 and is provided with a plurality of legs 45 which are suitably apertured at 46 to receive fastener screws 47 for securing the baffle in spaced relation with the oil pan bottom, and wherein a stop element 42' is provided integrally therewith and bent inwardly from one edge thereof.

In Fig. 9 another modification of the baffle 38 is illustrated, and therein the annular baffle body is provided with a plurality of upwardly bent integral fastener lugs 48 which may be riveted to the side wall of the

float 24 to secure said baffle below the float screen and in spaced relation thereto.

In operation, it will be obvious that the pipe 20 is buoyantly sustained in the oil pool 5 and that the inlet orifice of the elbow 28 of said pipe will always be held in communication with the oil pool at a point adjacent the surface thereof and remote from the oil pan bottom where water and deleterious matter 10 collect. It will also be evident that the pivotal mount of the suction pipe 20 enables the float 24 to readily adjust itself to the varying level of the oil pool when the latter is agitated or reduced in quantity for any 15 reason, and also that any ice formation, due to water accumulation, will be on the oil pan bottom and remote from the inlet orifice of the suction pipe elbow 28.

I claim:

20 1. In a device of the character described, and in combination, an oil pump, a pivotally mounted oil suction pipe adapted to swing in a vertical plane, an oil conduit connecting said suction pipe with the pump, a hollow 25 float element rigidly mounted upon said suction pipe, said float being made of sheet metal and provided with an annular peripheral groove formed in its side-wall, the bottom wall of said float being provided with radial- 30 ly arranged depending ribs to form channels therein, and a screen arranged over said bottom wall ribs and having its outer edge rigidly secured in said side-wall groove.

2. In combination, an internal combustion 35 engine provided with an oil pan or container, an oil pump, a floatable oil suction element operatively connected with said pump and provided with an oil inlet orifice, and a baffle plate carried by said oil suction element on 40 the under side thereof and spaced therefrom.

3. In combination, an internal combustion engine provided with an oil pan or container, an oil pump, a floatable oil suction element operatively connected with said pump and provided with an oil inlet orifice, a screen 45 mounted on the under side of said suction element, and a baffle plate carried by said oil suction element on the under side thereof and spaced therefrom.

50 4. The combination with an internal combustion engine provided with an oil pan or container and an oil pump, of a floatable oil suction element operatively connected with said pump and provided with an oil inlet orifice, and a baffle plate carried by said oil suction element on the under side thereof and spaced therefrom.

55 5. The combination with an internal combustion engine provided with an oil pan and an oil pump mounted relatively to said oil pan, of a pivotally mounted oil suction pipe operatively connected with said pump and adapted to swing in a vertical plane, a float connected with said suction pipe, a baffle 60 plate, and means for securing said baffle plate

on the under side of said float and spaced therefrom.

6. The combination with an internal combustion engine provided with an oil pan and an oil pump mounted relatively to said oil pan, of a pivotally mounted oil suction pipe operatively connected with said pump and adapted to swing in a vertical plane, a float connected with said suction pipe and provided with a screen on its under side, a baffle plate of substantially the same size as said float screen, and means for securing said baffle plate below said float screen and in spaced relation thereto.

7. The combination with an internal combustion engine provided with an oil pan and an oil pump mounted relatively to said oil pan, of an elbow adapted to be dependently connected with said pump, an oil suction pipe pivotally connected with said elbow and adapted to swing in a vertical plane, a float connected with said suction pipe, and a baffle plate carried by said float on the under side thereof and spaced therefrom.

8. The combination with an internal combustion engine provided with an oil pan and an oil pump mounted relatively to said oil pan, an oil suction pipe provided with an elbow which is pivotally connected with said oil pump on a horizontal axis, said suction pipe being adapted to swing in a vertical plane, a float connected with said suction pipe, and a baffle plate carried by said float on the under side thereof and spaced therefrom.

9. The combination with an internal combustion engine provided with an oil pan and an oil pump mounted relatively to said oil pan, of an elbow adapted to be dependently connected with said pump and providing a horizontal inlet, an oil suction pipe provided with an elbow which is pivotally mounted in said elbow inlet, said suction pipe being adapted to swing in a vertical plane, a float connected with said suction pipe, and a baffle plate carried by said float on the under side thereof and spaced therefrom.

10. The combination with an internal combustion engine provided with an oil pan and an oil pump mounted relatively to said oil pan, of a movably mounted oil suction element operatively connected with said pump, a float connected with said suction element, and provided with a screen on its under side, and a baffle plate mounted upon said float upon the under side thereof and spaced therefrom.

11. The combination with an internal combustion engine provided with an oil pan and an oil pump mounted relatively to said oil pan, of a movably mounted oil suction element operatively connected with said pump, a float connected with said suction element and provided with a screen on its under side, a baffle plate carried by said float upon the

under side thereof and spaced therefrom, and depending stop means carried by said baffle plate and adapted to engage the oil pan bottom.

5 12. In combination, an internal combustion engine provided with a base and an oil-pan, an oil pump, a pivotally mounted oil suction pipe operatively connected with said pump and adapted to swing in a vertical plane, a float connected with said suction pipe, a stationary baffle element arranged below said float and above the oil-pan bottom, and stop means to space said float from said baffle in the downward movement of said float.

10 13. In combination, an internal combustion engine provided with an oil-pan, an oil pump mounted relatively to said oil-pan, a pivotally mounted oil suction pipe operatively connected with said pump and adapted to swing in a vertical plane, a float connected with said suction pipe, and a baffle plate carried by said float on the under side thereof and spaced therefrom.

15 14. In combination, an internal combustion engine provided with an oil-pan, an oil pump mounted relatively to said oil-pan, a pivotally mounted oil suction pipe operatively connected with said pump and adapted to swing in a vertical plane, a float connected with said suction pipe, a baffle plate carried by said float on the under side thereof and spaced therefrom, and stop means to space said baffle plate from the oil-pan bottom.

20 15. In combination, an internal combustion engine provided with an oil-pan, an oil pump mounted relatively to said oil-pan, a pivotally mounted oil suction pipe operatively connected with said pump and adapted to swing in a vertical plane, a float connected with said suction pipe, a baffle plate carried by said float on the under side thereof and spaced therefrom, and stop means carried by said baffle plate to space the latter from the oil-pan bottom.

25 16. In combination, an internal combustion engine provided with an oil-pan, an oil pump mounted relatively to said oil-pan, a pivotally mounted oil suction pipe operatively connected with said pump and adapted to swing in a vertical plane, a float connected with said suction pipe, and a stationary baffle plate arranged below said float and provided with means for spacing the float from said baffle plate, the latter being fastened to the oil-pan bottom and in spaced relation thereto.

30 17. In combination, an internal combustion engine provided with an oil-pan, an oil pump mounted relatively to said oil-pan, an elbow connected with said pump, an oil suction pipe provided with an elbow which is pivotally mounted in said pump elbow to enable said suction pipe to swing in a vertical plane, a retaining element to hold said pump

elbow and suction pipe elbow in operative relation, a float element connected with the outer end of said oil suction pipe, and a stationary baffle plate arranged below said float above the oil-pan bottom and rigidly connected with said elbow retaining element.

35 18. In combination, an internal combustion engine provided with an oil-pan, an oil pump mounted relatively to said oil-pan, an elbow connected with said pump, an oil suction pipe provided with an elbow which is pivotally mounted in said pump elbow to enable said suction pipe to swing in a vertical plane, a retaining plate secured to said pump elbow to hold the latter and said suction pipe elbow in operative relation, a float member connected with said suction pipe, and upper and lower stop elements integral with said elbow retaining plate to limit the upward and downward swing of said suction pipe.
